UNITED STATES PATENT OFFICE.

EMILE VUILLARD, OF ST. CLAUDE, FRANCE, AND MAURICE STRAUSS, OF LONDON, ENGLAND.

ELASTIC MOUTHPIECE.

SPECIFICATION forming part of Letters Patent No. 794,061, dated July 4, 1905.

Application filed November 1, 1904. Serial No. 231,035.

To all whom it may concern:

Be it known that we, EMILE VUILLARD, residing at St. Claude, Jura, France, and MAURICE STRAUSS, residing at London, England, 5 citizens of the Republic of France, have invented certain new and useful Improvements in Elastic Mouthpieces; and we do declare the following to be a full, clear, and exact description of the invention, such as will enable others skilled in the art to which it appertains to make and use the same.

This invention relates to tobacco-pipes or cigar-holders, and more particularly to mouthpieces for this character of goods.

15 The object of this invention is to provide an elastic or resilient mouthpiece for tobacco-pipes and the like for the purpose of preserving the teeth of the smoker and at the same time to give a very firm hold of the 20 teeth upon the mouthpiece without an excessive grip of the teeth. An elastic mouthpiece for a tobacco-pipe is a very desirable feature, for the reason that a very slight hold upon the mouthpiece without setting the 25 teeth firmly thereon will hold the pipe in place without injuriously affecting the teeth of the smoker.

In the accompanying drawings, which form part of this specification, we have illustrated 30 an ordinary tobacco-pipe provided with our improved mouthpiece. It will be understood, of course, that such a mouthpiece may be applied to pipes of various kinds or to cigar-holders, cigarette-holders, and the like.

35 Figure 1 is a central longitudinal section through a pipe provided with a mouthpiece made in accordance with our present invention. Fig. 2 is a sectional view of a mouthpiece of slightly-modified form, and Fig. 3 is 40 an end view of the mouthpiece.

Referring to the drawings for a more par-

ticular description of the invention, the numeral 1 denotes the bowl of the pipe, which may be of ordinary construction. The mouthpiece 2 may be fitted to the stem portion of 45 the bowl in any suitable manner and a smoke-duct 3 extends through the mouthpiece, the bowl-stem, and into the bowl in the usual manner.

Our mouthpiece 2 may be made of vulcanized rubber or other suitable material having resilient inherent elasticity or resiliency sufficient to give the required yielding character to the mouth end of said mouthpiece. As shown in Fig. 1, an open slot 4 is formed in 55 the outer end of the mouthpiece, said slot extending into the mouthpiece a sufficient distance to render the two halves or sections 5 elastic or yielding, so that when taken between the teeth of the smoker and but 60 slightly gripped the pipe will be firmly held between the teeth. As seen in Fig. 3, the slot 4 extends entirely across the mouthpiece and the beads or nibs 6 are tapered off toward the sides of the slot 4 of the resilient sections 5. As shown in Fig. 2, the slot 4^a is of substantially V shape, and this construction may be resorted to when the material from which the mouthpiece is made is com- 65 paratively inelastic or non-yielding.

70 From the foregoing it will be obvious that our mouthpiece may be held between the teeth without excessive pressure and that a person with sensitive teeth will find great comfort in the use of such a pipe or mouth- 75 piece.

Various changes in the form, proportion, and the minor details of construction may be resorted to without departing from the principle or sacrificing any of the advantages of 80 this invention.

Having thus described our invention, what

we claim as new, and desire to secure by Letters Patent, is—

The herein-described mouthpiece made of resilient material, having a single smoke-duct and provided with a transverse slot at its outer end, said slot extending entirely across the mouthpiece and forming resilient sections or members, and the holding nibs or beads at the end of the mouthpiece tapering off toward the sides of said slot, substantially as described.

In testimony whereof we have hereunto set our hands in presence of subscribing witnesses.

EMILE VUILLARD.

MAURICE STRAUSS.
